(57) **CLAIM**

The ornamental design for a solenoid valve, as shown and described.

DESCRIPTION

FIG. 1 is a perspective view of a solenoid valve;

FIG. 2 is a perspective view of the solenoid valve;

FIG. 3 is a right side view of the solenoid valve;

FIG. 4 is a left side view of the solenoid valve;

FIG. 5 is a top view of the solenoid valve;

FIG. 6 is a bottom view of the solenoid valve;

FIG. 7 is a back side view of the solenoid valve; and,

FIG. 8 is a front side view of the solenoid valve.

The broken line showing of unclaimed portions of a solenoid valve form no part of the claimed design.
